United States Patent Office

Des. 206,212

Patented Nov. 8, 1966

206,212

COSMETIC CASE OR THE LIKE

Emmett H. Heitler, Denver, Colo., and Robert K. Fujioka, Los Angeles, and Tim M. Uyeda and Arthur W. Ellsworth, South San Gabriel, Calif., assignors, by mesne assignments, to Samsonite Corporation, Denver, Colo., a corporation of Colorado

Original design application Nov. 5, 1962, Ser. No. 72,389, now Patent No. 203,096, dated Nov. 30, 1965. Divided and this application May 5, 1965, Ser. No. 85,613

Term of patent 14 years

(Cl. D87—5)

FIG. 1.

FIG. 2.

FIG. 3.

FIG. 4.

FIG. 5.

FIG. 7.

FIG. 6.

FIG. 8.

FIG. 9.

FIG. 10.

FIG. 11.

FIG. 12.

FIG. 1 is a perspective view of a cosmetic case showing our new design;

FIG. 2 is a front elevational view thereof;

FIG. 3 is an end elevational view thereof;

FIG. 4 is a perspective view of the cosmetic case of FIG. 1, showing a modified embodiment thereof wherein the case top is provided with a peripheral groove adjacent the edges thereof;

FIG. 5 is a front elevational view thereof;

FIG. 6 is an end elevational view thereof;

FIG. 7 is a bottom plan view thereof;

FIG. 8 is an enlarged, fragmentary cross section thereof taken on line 8—8 of FIG. 6;

FIG. 9 is a perspective view of the cosmetic case of FIG. 1, showing a further modified embodiment thereof wherein the case top is more softly rounded at the edges thereof;

FIG. 10 is a front elevational view thereof;

FIG. 11 is a perspective view of the cosmetic case of FIG. 1, showing a further modified embodiment thereof wherein the case top is provided with the rounded edges

as in FIGS. 9 and 10 and wherein the parting line valance of FIGS. 1 through 10 is omitted; and

FIG. 12 is a front elevational view thereof.

In certain of the drawings, the handle, feet and details of the lock structure are shown in dotted lines for purposes of illustration only.

We claim:

The ornamental design for a cosmetic case or the like, as shown and described.
